Diamond
ATTORNEY,

UNITED STATES PATENT OFFICE.

SADIE NOVER, OF NEW YORK, N. Y.

HAND BAG.

Application filed July 17, 1922. Serial No. 575,612.

To all whom it may concern:

Be it known that I, SADIE NOVER, a citizen of the United States, and a resident of the borough of Manhattan, in the city, county, and State of New York, have invented certain new and useful Improvements in Hand Bags, of which the following is a specification.

The invention has for one of its objects 10 to provide a hand bag having two compartments or pockets, one of which is normally closed and so formed that its existence and the means of access thereto cannot be readily determined, the purpose being to provide 15 a hand bag having one pocket not readily accessible to a thief upon a surreptitious opening of the hand bag.

Another object of the invention is to provide 20 a hand bag having a body portion of fabric divided into two main compartments of substantially equal capacity and a main closure frame formed of hinged sections, and a supplemental closed frame adapted to be fitted in and lock to either member of the 25 main frame, whereby either one of the main compartments may be closed by the supplemental frame, leaving the other main compartment to be opened when the members of the main frame are separated.

30 Other objects and advantages of the invention will appear hereinafter.

In the drawings, Fig. 1 is a plan view of the frame of the hand bag, the fabric being removed therefrom;

35 Fig. 2 a transverse sectional view of the hand bag showing the fabric forming the pockets and secured to the frame;

40 Fig. 3 a detail transverse sectional view showing the main and supplemental frames locked together in closed position, with the supplemental frame in the position shown in Fig. 1;

45 Fig. 4 a plan view of the frame, the supplemental or inner frame being connected to the opposite side of the main frame from the position shown in Fig. 1;

50 Fig. 5 a transverse vertical sectional view showing the fabric pockets attached to the frame and the supplemental frame in the position shown in Fig. 4; and

55 Fig. 6 a detail transverse sectional view of the frames locked together, with the supplemental frame in the position shown in Fig. 5.

Referring to the various parts by nu-

merals, 1 designates the body portion of the bag which may be formed of any suitable fabric or flexible material. The edges of the open upper end of the body portion are secured in two main rigid channel members 60 3 and 4, preferably formed of sheet metal. The channel members are formed at their ends with extensions or lugs 5 and 6, said lugs being connected together by pivot pins 7 extending through apertures therein. As 65 shown in the drawings, these channel members, when they are in open position as shown in Figs. 1 and 4, form a rectangle and permit free access to the interior of the body portion. It is obvious however, that 70 the main channel members may have any other desired conformation.

The body portion 1 of the bag is divided 75 into two compartments of substantially equal capacity by a division wall 8. The upper end of the partition or wall 8 is suitably secured in a supplemental channel member 9 having lugs or extensions 10 at its ends, which lugs or extensions are pivotally held to the hinged pins 7 of the main frame 80 members. The supplemental channel member 9 is adapted to fit within either one of the main frame members 3 or 4 and to lie in the same plane thereof. As shown in Fig. 1 the supplemental frame member 9 is 85 connected to the main frame member 4, while in Fig. 4 it is shown as connected to the main frame member 3. The division wall 8 serves to divide the bag into two 90 pockets 11 and 12, either one of which may be closed by locking the supplemental frame member 9 to one of the main frame members 90 3 or 4.

95 The supplemental frame member 9 is provided with a pivoted latch 13 adapted to be operated by a finger piece 14. When the supplemental frame member is locked to the main frame member 4 the pocket 12 will be normally closed and the finger piece 14 will be exposed by opening or separating the 100 main frame member. When the supplemental frame member 9 is locked to the main frame member 3 the finger piece 14 will be concealed within the pocket 11, as shown in Fig. 5 of the drawings. The latch 105 13 is adapted to be turned up into the channel member 3 or 4 in order to lock the supplemental frame member in position.

On the pivot pins 7 are mounted pivoted frames 15 to which may be secured a suit- 110

able fabric pocket 16 to form a small central pocket which may be used as a receptacle for money or valuables. The pocket 16 is contained within the main pocket 11, and 5 when the supplemental frame 9 is locked to the main frame member 3 this pocket 16 is closed and concealed within said pocket 11. When the supplemental frame 9 is locked to the main frame member 4 the pocket 16 10 is direct-exposed when the main frame members are separated and swung outwardly on their pivots.

The latch 13 swings to lock the supplemental frame to the main frame members 15 against movement in either direction. If it be desired the supplemental frame may be turned down within the bag so that both of the pockets 11 and 12 will be normally open when the main frame members are 20 separated. This is indicated in dotted lines in Fig. 5.

When the supplemental frame is locked to the main frame member 3 the finger piece 14, for operating the latch, may be manipulated either from the outer side of the bag 25 or from the inner side thereof by pressing inwardly the fabric walls. These walls are flexible and readily permit the finger piece to be operated although it is concealed with- 30 in the pocket 11.

It will, of course, be understood that a suitable carrying strap may be attached to the eyes 17 secured to the main frame. It will also be understood that the two main 35 frame members are secured together in their closed position by snap fasteners 18; and that the two members of the inner pocket 16 are adapted to be secured together by the two snap fasteners 19.

40 What I claim is:

1. A hand bag frame comprising a pair of main frame members, a supplemental closure frame member conforming in contour to the closure frame members and adapted 45 to fit closely in either of said members, and locking means carried by the closure frame member and adapted to lock the said member to either of the main frame members with its exposed face flush with the inner 50 face of the main frame member.

2. A hand bag frame comprising a pair of main frame members, a supplemental closure frame member conforming in contour to the closure frame members and adapted 55 to fit closely in either of said members, and locking means carried by the closure frame members and adapted to lock the said member to either of the main frame members with its exposed face flush with the inner 60 face of the main frame member, the said locking means being disposed entirely within the outer edge of the supplemental frame member in unlocked position and projecting outwardly from said edge in locked position to engage either of the main frames.

3. A hand bag frame comprising a pair of main frame members, a supplemental closure frame member adapted to fit within either of the main frame members, a pair of pivot pins connecting the ends of all the 70 frame members together, the said supplemental frame member being of channel form, and a latch mounted upon the supplemental frame member within its channel space and adapted to be moved to lockingly 75 engage either of the main frame members, the supplemental frame and its latch being adapted to be swung through the main frame members.

4. A hand bag comprising a pair of main frame members, a main flexible body portion connected to and around the edges of said main frame members, a supplemental closure frame member adapted to fit within either of the main frame members, a flexible 80 dividing wall or partition connected to the supplemental frame member and to the main body portion of the bag to divide the said body portion into two pockets, pivot pins connecting the ends of all of the frame members together whereby they will swing about the same axis, the said supplemental frame member being adapted to be forced through either of the main frame members and swung down within the bottom of the bag 85 whereby the dividing wall forms two open pockets, a latch carried by the supplemental frame member and adapted to releasably lock said member to either of the main frame members, and means for releasably locking 90 the main frame members.

5. A hand bag comprising a pair of main frame members, a main flexible body portion connected to and around the edges of said main frame members, a supplemental closure frame member adapted to fit within one of the main frame members, a flexible dividing wall or partition connected to the supplemental frame member and to the main body portion of the bag to divide the said body portion into two pockets, pivot pins 100 connecting the ends of the frame members, the said supplemental frame member being adapted to be forced through one of the main frame members and swung down within the bottom of the bag 105 whereby the dividing wall forms two open pockets, a latch carried by the supplemental frame member and adapted to releasably lock said member to one of the main frame members, and means for releasably locking 110 together the main frame members.

6. A hand bag comprising a pair of main frame members, a main flexible body portion connected to and around the edges of said 115 main frame members, a supplemental closure frame member, a flexible dividing wall or partition connected to the supplemental frame member and to the main body portion of the bag to divide the said body portion 120 of the bag to divide the said body portion 125 of the bag to divide the said body portion 130

into two pockets, pivot pins connecting the ends of all of the frame members together whereby they will swing about the same axis, and a latch carried by the supplemental frame member and adapted to releasably lock said member to one of the main frame members, the said latch being concealed by the flexible dividing wall when the supplemental frame member is locked to the main frame member and adapted to be released through the flexible wall.

7. A hand bag comprising a pair of main frame members, a main flexible bag portion connected to and around the edges of said main frame members, a supplemental closure frame, a flexible dividing wall or partition connected to the supplemental frame member and to the main body portion of the bag to divide the said body portion into two

pockets, pivot pins connecting the ends of all of the said frame members together whereby they will swing about the same axis, a purse comprising a pair of frames pivotally mounted within the supplemental frame and a flexible pouch, and a latch carried by the supplemental frame member and adapted to releasably lock said member to one of the main frame members, the said latch and the said purse being concealed by the flexible dividing wall when the supplemental frame member is in locked position against the main frame member and the said latch being adapted to be released through the said flexible wall.

In testimony whereof I hereunto affix my signature.

SADIE NOVER.
